TAPE ERASER

Edward D. Garner, 4200 N. 48th,
Lincoln, Nebr. 68504

Filed July 14, 1975, Ser. No. 595,764

Term of patent 14 years

Int. Cl. D14—02

U.S. Cl. D26—1 M

FIG. 1

FIG. 2

FIG. 3

FIG. 4FIG. 5FIG. 6FIG. 7FIG. 1 is a perspective view of a tape eraser showing my new design.

FIG. 2 is a top plan view thereof,

FIG. 3 is an elevational front side view thereof,

FIG. 4 is a bottom plan view thereof,

FIG. 5 is an elevational rear side view thereof,

FIG. 6 is an end view of the end at the left side of FIG. 2; and

FIG. 7 is an end view of the end at the right side of FIG. 2.

The electrical cord is shown broken away on the drawings to indicate indeterminate length.

I claim:

The ornamental design for a tape eraser, as shown and described.
